SWITCH

John B. Parsons, Maumee, Ohio

Application March 17, 1950, Serial No. 8,597

Term of patent 7 years

(Cl. D26—13)

To all whom it may concern:

Be it known that I, John B. Parsons, a citizen of the United States and a resident of Maumee, Lucas County, Ohio, have invented a new, original, and ornamental Design for a Switch, of which the following is a specification, reference being had to the accompanying drawing, forming a part thereof.

In the drawing:

Figure 1 is a perspective view of the switch, showing my new design;

Figure 2 is a top plan view of the switch; and
Figure 3 is a side elevation of the switch.

The design is indicated by the solid line portion of the drawing.

I claim:

The ornamental design for a switch, as shown and described.

JOHN B. PARSONS.
